Inventor:

George E. Pickup,
By Chindell Parker Ballou, Attns.

UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

CIRCULATING HEATING STOVE.

Application filed March 23, 1928. Serial No. 264,154.

The invention relates generally to circulating heating stoves and more particularly to stoves of this type in which the heating unit is enclosed in a concealing cabinet 5 preferably adapted and constructed to present a finished and ornamental appearance.

One object of the invention is to provide a new and improved cabinet for enclosing a heating unit which embodies a closure 10 means therefor of a simple and practical character movable to an out of the way position to permit access to the interior of the cabinet for operating purposes.

Other objects and advantages will become 15 apparent in the following description and from the accompanying drawings in which:

Figure 1 is an elevational view of the invention, parts thereof being broken away to disclose the operation of the closure 20 means.

Fig. 2 is a fragmentary view in perspective taken from the interior of the cabinet looking outwardly.

Fig. 3 is a fragmentary view in elevation, 25 looking laterally from the interior of the cabinet, of one of the closure sections in open position.

Figs. 4 and 5 are enlarged fragmentary detail views in section and plan respectively 30 showing the upper guide bar and follower.

Figs. 6 and 7 are enlarged fragmentary side and face views respectively showing the construction of the lower guide rails and rollers.

While the invention is susceptible of various modifications and alternative constructions, I have shown in the drawings and will herein describe in detail the preferred embodiment, but it is to be understood that I 40 do not thereby intend to limit the invention to the specific form disclosed, but intend to cover all modifications and alternative constructions falling within the spirit and scope of the invention as expressed in the appended claims.

In the drawings a cabinet, constructed in accordance with the objects of this invention, is shown as comprising generally an upright outer case or cabinet having a top 50 10, bottom 11, and a front, back and sides. If desired suitable legs 15 may be employed to space the cabinet from the floor. The cabinet is of a size to enclose a suitable heating unit or stove, generally designated 55 as 16, which may be of any preferred con-

struction and design. The cabinet may be as ornamental in appearance as is desired and preferably the ornamentation is of such character that designs in grille work 17 or the like may be employed. Thus a free circulation 60 through the cabinet, of air to be heated by the stove mounted therein, is insured without detracting from the appearance of the cabinet.

As shown the stove is mounted in the cabinet with the fuel and ash pit doors 18, 19, which are customarily provided in such stoves, facing toward the front of the cabinet. In order that access to the doors 18, 19 may be had, the front of the stove has an 70 opening, the margins of the opening being defined by a frame 20 which may be formed as an integral part of the front or may be rigidly affixed thereto. Preferably the upper edge of the frame is turned inwardly 75 to provide a short flange 21 (Fig. 4) the purpose of which will become hereinafter apparent.

In the present embodiment the preferred form of closure means (Figs. 1 and 2) comprises a pair of flat substantially rectangular doors 22 which are adapted normally to extend across and completely close the front opening of the cabinet. A simple form of means for insuring that the doors assume 80 the proper position in the frame and for providing rigidity between the doors comprises an offset lug 22^a projecting laterally from a position near the top and bottom of 85 the inner edge of one of the doors, which lug 90 is adapted to engage a complementary boss 22^b formed in proper position upon the other door. Any suitable form of operating handles 23 may be secured in the customary manner upon the doors 22.

The means by which guided movement of the doors is attained comprises, in the present instance, a pair of guide wheels, generally designated as 24, mounted near the lower edge of each of the doors, which 95 wheels engage suitable guide rails 30, 31 shaped properly to direct and guide the movement of each door. Means also is provided on each door to support the upper portions thereof during the opening and closing movements.

The guide wheels 24 may be of any suitable form, and in the present instance comprise grooved rollers 25 (Figs. 6 and 7) each of which is pivotally mounted on an L- 110

shaped bracket 26 which carries a vertically extending rod 27. The rod 27 is journaled in both legs of a U-shaped bracket 28, which in turn is rigidly fixed to a pair of lugs 29 suitably mounted upon the door. Thus, each of the rollers 25 is spaced inwardly of the cabinet from the doors, and are mounted in such manner that relative pivotal movement is permitted.

10 The guide rails 30, 31 are in the form of tracks provided for each door and are mounted upon the bottom of the cabinet in a position to be engaged by the grooved rollers 25. As may be seen in Fig. 2, four 15 guide rails are shown, there being a set of two rails for each of the doors. The inner rails 30 of the sets are appropriately formed and positioned relative to the doors so that as the inner rollers follow the rails the inner 20 side of the doors will move in a substantially straight line laterally of the cabinet. The outer rails 31 are curved so that as the outer rollers follow the rails the outer side of the doors move first diagonally inwardly a short 25 distance and then swing rearwardly to occupy a position near the rear corners of the cabinet.

Means is provided for guiding and supporting the upper portion of the doors during the movement thereof. This means, in 30 the present instance, comprises a guide bar 32 (Fig. 4) secured to a plurality of lugs 33 which space the bar rearwardly from the front of the cabinet with the bar extending 35 laterally across the cabinet substantially in registry with the margin of the upper edge of the frame 20. Each of the doors carries an upwardly extending follower herein shown in the form of a finger 34, which is 40 rigidly secured to lugs 35 preferably positioned near the inner upper corners of the doors. The fingers 34 on the doors are adapted to be inserted between the inwardly extending flange 21 on the upper side of 45 the frame 20 and the guide bar 32 for guided sliding movement therebetween.

The operation of the closure means for the cabinet is simple. Assuming that the doors are in closed position and that it is 50 desired to open them, it is only necessary to grasp the operating handles 23 and to exert a force acting to separate the handles. Such a force will cause the outer edges of the doors to move diagonally inwardly a 55 short distance, and then as the outer rollers follow the guide tracks 31, these edges of the doors will be swung sharply inwardly of the cabinet. At the same time the inner edges of the doors have been guided by the inner 60 rollers upon the inner guide rails 30 to a position adjacent the front side of the cabinet. Thus in the open position of the doors only the inner edges thereof may be seen.

By this construction it will be apparent 65 that a closure means for the front opening

of the cabinet has been provided which is simple in construction and which may be readily and easily moved to an out-of-the-way position at the sides of the cabinet when it is necessary, for any reason, to obtain access to the heating element positioned in the cabinet. 70

I claim as my invention:

1. A circulating heating stove comprising, in combination, a stove body, a cabinet 75 adapted to enclose said body and having side walls spaced from the body and openings adjacent the top and bottom thereof, whereby to permit circulation of air through the cabinet, said cabinet having an opening 80 through one of its sides through which access to the stove is obtained, and a pair of doors adapted normally to close the opening and movable from a position closing said opening to out-of-the-way positions into the 85 spaces between the sides of said cabinet and said body.

2. A circulating heating stove comprising, in combination, a stove body having an opening in its forward side and a hinged door 90 closing said opening, a cabinet adapted to enclose said body and to cause circulation of air about said body and having an opening in its front face through which access to the stove door is obtained, and a door 95 guided for movement from a position closing said opening in the cabinet to a position between said body and said cabinet.

3. A circulating heating stove comprising, in combination, a stove body, a cabinet 100 adapted to enclose said body and to provide an air circulating space around said body, said cabinet having apertures at the top and bottom thereof to permit circulation of air through said space and further having an 105 opening of substantial size in the front side thereof through which access to the stove body is obtained, a pair of doors adapted normally to close said opening, each of said doors being movable from the normal position 110 thereof to an out-of-the-way position in said space, and means for guiding the said doors in such movement, said guide means comprising parts engaging the outer edges of said doors to guide said edges rearwardly and other parts engaging the inner edges of said doors to guide said inner edges laterally of the opening whereby said doors move swingingly around the adjacent portions of said stove body to said out-of-the-way positions in said space. 115

4. A circulating heating stove comprising, in combination, a stove body, a rectangular cabinet adapted to enclose said body and to provide an air circulating space around said body, one face of said cabinet having an opening through which access to the stove body is obtained, a pair of movable doors adapted normally to close said opening, and guide means in said space for directing the 120 125 130

- movement of said doors to out-of-the-way positions substantially paralleling the walls of said cabinet within said air-circulating space.
- 5 5. A circulating heating stove comprising, in combination, a stove body, a cabinet adapted to enclose said body and to provide an air circulating space within said cabinet and around said body, said cabinet having
- 10 a portion of its front face open to permit access to said body, a pair of doors normally closing said open portion, guide means on said cabinet extending laterally thereof, means near the abutting inner edge of said
- 15 doors engaging said guide means to effect a lateral movement of said door edges to a position substantially adjacent the side walls of said cabinet, other guide means on said cabinet extending substantially in a front to rear direction thereof, and means near the 20 outer edges of said doors engaging said last mentioned guide means to effect a rearward movement of said door edges, said last mentioned guide means being shaped to guide said door edges first rearwardly a short distance then laterally to a position adjacent the side walls of the cabinet, and thence rearwardly.

In testimony whereof, I have hereunto affixed my signature.

GEORGE E. PICKUP.
